UNITED STATES PATENT OFFICE.

GEORGE W. YEARICKS, OF PHILADELPHIA, PENNSYLVANIA.

DESIGN FOR A FOOT-REST.

SPECIFICATION forming part of Design No. 25,848, dated July 28, 1896.

Application filed May 22, 1896. Serial No. 592,685. Term of patent 7 years.

To all whom it may concern:

Be it known that I, GEORGE W. YEARICKS, a citizen of the United States, residing at Philadelphia, (Bridesburg,) in the county of Philadelphia and State of Pennsylvania, have invented and produced a new and original Design for Foot-Rests, of which the following is a specification, reference being had to the accompanying drawings, forming part thereof, and in which—

Figure 1 is a perspective view of a foot-rest, showing my design; and Fig. 2 is a cross-sectional view on the line $x x$ of Fig. 1, these two views being deemed essential to fully illustrate my design.

The leading feature of my design consists in the essentially T-shaped outline of the foot-rest, the stem and top of the T being both substantially rectangular in outline.

Referring to the drawings, A is the upper or top rectangular shape panel. From approximately the center and at right angles thereto depends the stem B, also of substan-

tially rectangular shape. The ends of the top A are concavely cut out, as at D, and the lower end of the stem B is similarly shaped, as at E. From the side edges of the panel A, at approximately the meeting-point of the panel A with the panel B, is arranged the depending pyramidal-shaped ornaments F, having the converging sides concave, as at G.

Having thus described my invention, what I claim as new, and desire to secure by Letters Patent, is—

The design for a foot-rest of a T shape in outline and the stem and body thereof substantially rectangular, as herein shown and described.

In testimony whereof I have hereunto set my signature in the presence of two subscribing witnesses.

GEO. W. YEARICKS.
